UNITED STATES PATENT OFFICE.

ZELA L. BEDFORD, MORRIS F. HIGGINS, JR., AND CARL C. HIGGINS, OF LIMA, OHIO.

MOTOR-VEHICLE.

1,196,643.

Specification of Letters Patent. Patented Aug. 29, 1916.

Application filed February 26, 1916. Serial No. 80,724.

To all whom it may concern:

Be it known that we, ZELA L. BEDFORD, MORRIS F. HIGGINS, JR., and CARL C. HIGGINS, citizens of the United States, and residents of Lima, in the county of Allen and State of Ohio, have invented an Improvement in Motor-Vehicles, of which the following is a specification.

This invention is an improvement in motor vehicles and has particular reference to constructions for supplying a motor fluid to the engine.

An object of the invention is to dispense with the use of gasoline and substitute natural or artificial gas therefor and to this end there is provided a supply tank or tanks mounted upon the vehicle and connected to the intake manifold of the engine by a suitable supply pipe.

The inventive idea involved is capable of receiving a variety of mechanical expressions, one of which, for the purpose of illustrating the invention, is shown in the accompanying drawing, in which the figure illustrates, in side elevation, a motor vehicle with the invention applied thereto.

Referring more particularly to the drawing the numeral 1 indicates a motor vehicle of any preferred construction having the usual engine 2 provided with the intake manifold 3.

Preferably at the rear of the machine the same has mounted a pair of superposed supply tanks 4 and 5 connected by a short length of pipe 6, the upper tank having an inlet closed by a suitable cap 7 for the purpose of filling the tanks. The upper tank 5 is also provided with a gage for indicating the pressure in the tanks while the lower tank 4 has a safety blow-off valve 9 for permitting the escape of the gas from the tanks should the pressure therein become too great. The lower tank 4 also has leading therefrom

a supply pipe 10 which is provided adjacent said tank with a pressure reducing valve 11 for the purpose of allowing the gas to pass from the tanks at an even pressure. Adjacent the valve 11 the pipe is provided with a stop cock 12 for regulating the amount of gas passing through the pipe. At the other end of the latter there is shown conventionally an air intake 13 and gas control 14, for the purpose of providing the proper mixture, said gas control being operated by a rod 14' which leads to the steering wheel of the machine. The pipe 10, at its extremity, is connected to the intake manifold 3 of the engine in order that the mixture may be fed thereinto.

It will thus be seen that the invention provides a structure in which natural or artificial gas may be substituted for gasoline and the same properly mixed with air in order to supply a motive fluid for driving the engine.

What is claimed is:

In a motor vehicle, the combination with an engine having an intake manifold, superposed gas containing tanks mounted in the rear of the vehicle, a connection between said tanks, a gage mounted on one of said tanks, a blow-off valve carried by the other tank, a supply pipe leading from one of said tanks to the intake manifold of the engine for feeding gas thereto to accomplish a continuous operation of the same, a pressure reducing valve mounted in said pipe adjacent said tanks, a stop cock also mounted in said pipe, means for admitting air to said intake manifold, and means operable from the driver's seat of the vehicle to control the last-named means.

ZELA L. BEDFORD.
MORRIS F. HIGGINS, JR.
CARL C. HIGGINS.
